SPACER

Edward M. Penneck, Minneapolis, Minn., assignor to G. H. Tennant Company, Minneapolis, Minn., a corporation of Minnesota

Application July 30, 1928. Serial No. 296,284

7 Claims. (Cl. 217—20)

My invention relates to a spacer which is particularly adapted for crates such as are used for milk bottles and other containers. The primary object is to provide a spacer adapted to form a brace between the partition members in the crate which not only properly spaces the respective partition members crossing each other, but ties them together in a manner to form a rigid, firm construction of a desirable nature to the crate.

10. A feature of the invention resides in means for connecting the cross wires of a milk bottle crate in a manner so that the wires are tied together with a simple, inexpensive means, easily assembled in the manufacture of the crates.

15. This means of tying the members together provides a spacer and is particularly adapted to wire partition members.

In milk bottle crates it is desirable to use wire partitions formed by spacing two or more parallel wires superimposed and extending to the side walls of the crate. These wires are crossed in the formation of transverse and longitudinal partitions in the crate and it is desirable that they be connected together in a manner to form 25 a comparatively firm substantial partition which will keep their shape under severe use and hard handling. My spacer is desired to accomplish these results as will be more fully hereinafter pointed out. In handling crates with these wire partitions they are often engaged by the wire partitions and lifted and moved about, and I find that my crate construction with these spacers ties the wire members forming the partitions together in such a manner that the strain 30 is distributed equally to the respective wires and thus forming a sturdy strong construction which will withstand the hard use to which these crates are placed.

Other features and objects will be more fully 40 hereinafter pointed out.

In the drawing Figure 1 illustrates a plan view of a portion of a crate showing my spacer.

Figure 2 is a perspective under view of the spacer in enlarged formation.

45. Figure 3 is a side view in one direction of the spacer.

Figure 4 is a side view in one direction of the spacer.

50. Figure 5 is a side elevation of a portion of a crate.

The drawing illustrates my spacer A which is made of sheet metal of any desired thickness to provide the necessary rigidity to the same. The spacer A is formed of a single piece of sheet material and is adapted to engage the partition

wires 10 and 11 to connect the same together and to space the wires in such a manner as to form a brace at the intersection of the same.

The wires 11 form the transverse partition wires of the crate B. The transverse partition wires 11 extend across the crate B and are anchored in the side members 12 in any suitable manner. These partition members 11 extend parallel and superimposed to each other as illustrated in the side view of Figure 5.

The longitudinal partition wires 10 are also parallelly positioned to each other and are superimposed. The wires 10 and 11 extend in close relation to each other so that where they cross they virtually touch or contact, as illustrated in Figures 2 to 4 inclusive.

The spacer plate A is shaped with sloped sides 14 projecting downwardly from the top ridge 15. These plates may be made virtually square with depending or sloping sides 14 and perforated 75 with slots 16 through which the wire partition member 11 is adapted to extend. The top ridge 15 forms a channel-like portion which is adapted to receive the wire partition member 10 and by means of the depending sides 17 the plate A is 80 reinforced along the edges. The depending sides 17 are formed of an angular shape starting from the corners 18 and sloping with increasing width to the end 19 so as to form shoulders 20 by the ends of the wall which are adapted to engage 85 the rod 10 which extends along the inside of the ridge 15.

Thus the side walls 17 provide a depending strengthening rib for the plate A and also provide the shoulders 20 between which the wire 10 90 passes so as to space the wire in the plate A. The openings 16 engage or receive the wires 11. The wire 11 extends directly below the wire 10 and the portion 22 at the corner 18 of the plate A engages beneath the wire 11 and thus forms a tie with the engagement of the inside of the ridge 15 by the wire 10 to tie the two wires 10 and 11 together by placing a plate A at their intersecting point. These plates A are formed so that the wires can be slid through the plate and the openings 16 are formed so that a slight tension of the portions 22 against the wire 11 causes the wire 11 to bear with a slight tension against the wire 10 and in a sense holds the wires 10 and 11 in contact with each other by a slight spring nature of the plate A. This provides a good substantial construction and forms a brace in the plate A at the intersecting points of the wires 10 and 11.

In making my crate B I prefer to use the plates 110

A on the top wires 10 and 11 of the crate B, as illustrated in Figure 5.

The plate A is used at the intersecting points of the wires 10 and 11 at the uppermost wires of the partition ordinarily, however, when three wires or more than two wires are used in the height of the partitions formed by the wires 10 and 11, then the plates A may be used at the intersecting points of these wires below the top wires.

10 Or if it is desired, the brace plates A may be used at all of the intersecting points of the wires 10 and 11.

The spacers A are adapted to form a means in the compartments for holding the bottles in one compartment from contacting with the bottles in the adjacent compartment. In use the milk bottle crates B receive considerable wear and tear and as the bottles are handled in these crates, they shift in the compartments quite readily. It is necessary that they fit free in the respective compartments and by means of my spacer, the bottles are separated one from the other so that breakage is overcome, thereby providing a very desirable means of spacing the bottles and at the same time functioning to hold the wires in proper spaced relation yet giving sufficient spring to the wire partitions to prevent rigid jarring against the bottles.

When the plates A are only used on the top partitions wires 10 and 11, then angle iron connecting members C, which will be hereinafter described, may be used to connect the lower wires with the topmost wires.

The upper wires 10 and 11 of the crate B may be connected together by the angle iron members C so as to tie the wires 10 and 11 which form the partitions for the crate B together. The angle irons C are formed with one side 23 which extends up and in which a hole is punched to receive the wire 11. The other side is cut away at 24 so as not to interfere with the plate A. These angle iron members C extend as illustrated in Figure 5 and connect the partition wires 10 and 11 together by means of suitable holes formed in the angle iron members C which receive the respective wires. The center angle members C extend down to engage a lower partition wire 11 and this wire 11 is adapted to extend below the crate bottom wires 25 so that these center angle members C carry the load on the bottom wires 25 which form the bottom of each of the bottle compartments 26 in the crate B to the other partition wires 10 and 11. Thus the angle members C assist to distribute the load from the respective wires and by means of the partition plate A I provide braces on the top partition wires which properly space the same apart and which form plate-like members at the intersections of the top respective partition wires 10 and 11. This structure for the crate B gives a sturdy substantial construction adapted to receive wear and tear in the use of these crates.

In handling the crates B they are often engaged by the partition wires 10 or 11 and lifted and unless these wires are properly braced they will bend out of shape and the crates will soon become ineffective in serving the purpose desired, because if the partition wires 10 and 11 become bent and unshapely, then the bottles held in the respective compartments 26 will strike against each other and easily break in the handling of the crates of bottles. Thus it is evident that the keeping of the partition wires shapely and in proper position is of primary importance.

75 In accordance with the patent statutes I have

described my crate and illustrated the best embodiment of my respective elements making up the same, I desire to have it borne in mind, however, that obvious changes may be made within the scope of the following claims without departing from the intent and purpose of the invention.

I claim:

1. A spacer including, a plate-like body member formed of a single sheet of springy material, 85 depending flange members extending from the sides of said spacer having a sloping formation in a manner to decrease in width from one corner to the other of said spacer, the extreme width of said flange members forming shoulders at two of the corners of said spacer, a ridge extending through the body of said spacer to the corners from which said shoulders project to receive a wire from corner to corner between said shoulders adapted to lie in said ridge along the bottom of said spacer, and openings formed in the opposite corners of said spacer adapted to receive a second wire to hold the same under spring tension over said spacer against the bottom of said first wire, said wires forming the 100 partition members of a crate.

2. A spacer for crates adapted to engage the wire partition members at the intersecting points to hold the same together under spring tension of the spacer, said spacer including a single piece 105 springy plate member, means formed in said plate to receive the partition members extending transversely to each other to hold the same together by the spring tension of said plate and to form a brace spacer to hold the partition 110 wires square at their intersecting points.

3. A crate including, a series of wire partition members adapted to intersect each other at right angles and engage with each other at the intersecting points, spacer plates having a channel 115 formed by said plates and by flanges depending therefrom to receive one of the spacer wires in one direction, and openings in the sides of said spacer to receive the wire partition member extending in the other direction, and members extending below the topmost wire partition member 120 flexibly connecting and holding properly spaced the wire partition members in a manner to distribute the strain of the wire partition members from one to the other wire and to the lower- 125 most wires in said crate.

4. A spacer plate for crates adapted to engage the wire partition members at their intersecting points including, a body portion bent with a ridge forming a wire receiving channel from one corner to the other, flat sloping sides of a triangular nature extending from said ridge, wire receiving openings in said sloping sides, a separate flange member formed along each side of said spacer and depending therefrom reinforcing the 130 flat wire receiving sides, starting at the corners of said sloping sides and increasing in width toward the corners through which said ridge extends and shoulders formed by said flanges adjacent said last named corners to hold a partition 135 member in said channel.

5. A spacer for wire partitions of a crate comprising, a springy plate-like body, said plate being bent to form a wire receiving channel extending through two opposite corners of said plate, 145 the formation of said channel providing depending top sides extending toward the two opposite corners of said spacer, slots in said depending sides adapted to receive a wire partition member directly below the wire partition member adapted 150

to extend through said channel to hold the wire partition members in contact under spring tension at their intersection, and depending flange members adapted to form shoulders for engaging the wire partition members extending through said channel.

6. A spacer for crates including, a square springy plate-like member, a wire receiving channel formed from corner to corner of said plate, and wire receiving slots extending adjacent the two opposite corners through which said channel extends whereby two intersecting partition wires may be connected together under spring tension of said spacer by passing one wire through

said channel and the other through said slots.

7. A spacer for intersecting wire partition members of a crate including, a rectangular plate member formed of a single piece of springy sheet material, a ridge formed by bending said sheet diagonally, a groove formed by the bending of said plate to contain one wire partition member, and openings formed in said plate oppositely disposed on either side of said ridge through which the other partition member may extend when said spacer is bent under spring tension to pinch said one partition member against said plate.
